CLAIM

The ornamental design for a storage pack, as shown and described.

DESCRIPTION

FIG. 1 is a front, top, and right side perspective view of a storage pack, which embodies our design.

FIG. 2 is a rear, bottom, and left side perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

(Continued)

The broken lines in the drawings illustrate portions of straps of the storage pack, which form no part of the claimed design.
